UNITED STATES PATENT OFFICE.

JAMES S. JOHNSTON AND MORGAN M. HOGAN, OF UTICA, NEW YORK; SAID HOGAN AS-
SIGNOR, BY MESNE ASSIGNMENTS, TO RANDOMTEX DYEING MACHINE CORPORA-
TION, OF SYRACUSE, NEW YORK, A CORPORATION OF NEW YORK.

METHOD FOR PRODUCING INTERMITTINGLY COLORED YARNS.

Original application filed August 29, 1923, Serial No. 659,974. Divided and this application filed October 22, 1923. Serial No. 670,203.

This invention relates to a method for producing intermittently colored yarn on the bobbin whereby to produce spotted or streaked color effects when knitted or woven into fabric, as a division of our pending application, Serial Number 659,974 filed August 29, 1923.

The main object is to provide a more expeditious method of producing these spotted or streaked effects by dipping a limited portion such as one end or both ends of a bulk winding or bobbin of the yarn into a suitable coloring matter.

The drawing represents diagrammatically, an apparatus for carrying out the process and consists of a vat —1— containing a body of liquid coloring matter —2— for receiving one end or both ends of a wound bulk or bobbin —3— of yarn in such manner as to color or die a limited portion of the bulk.

That is, the process consists in winding a considerable quantity of yarn upon any suitable support around and lengthwise of a common axis so as to produce a multiplicity of layers of yarn one upon the other and then immersing a limited portion such as one end or both ends of the wound bulk into

a liquid die or coloring matter, whereby when the yarn is unwound and knitted or woven into a fabric, the colored portions of the yarn will appear in spots or streaks as distinguished from the uncolored portions.

What we claim is:

1. The herein described method of producing intermittently colored yarn consisting in winding the yarn upon a bobbin so as to form a multiplicity of layers, and dipping relatively small portions only of the wound yarn upon the bobbin into a coloring liquid so as to leave the remaining portions of the yarn uncolored.

2. The herein described method of producing intermittently colored yarn in which the yarn is wound upon a core so as to form a multiplicity of layers around the axis of the core, dipping a portion of the wound body of yarn extending from the core to the periphery of said body into a coloring liquid so as to color a portion of each layer of the yarn.

In witness whereof we have hereunto set our hands this 13th day of October, 1923.

JAMES S. JOHNSTON.
MORGAN M. HOGAN.
